UNITED STATES PATENT OFFICE.

JAMES A. LITTLE, OF BISMARCK, NORTH DAKOTA.

WATER-HEATER FOR GAS OR GASOLENE STOVES.

1,225,834.

Specification of Letters Patent. Patented May 15, 1917.

Application filed August 26, 1916. Serial No. 117,053.

To all whom it may concern:

Be it known that I, JAMES A. LITTLE, a citizen of the United States, residing at Bismarck, in the county of Burleigh and State 5 of North Dakota, have invented certain new and useful Improvements in Water-Heaters for Gas or Gasolene Stoves, of which the following is a specification, reference being had to the accompanying drawings.

10 This invention relates to an improved water heater for gas or gasolene stoves and has for its primary object to provide a very simply constructed and inexpensive device for the purpose of quickly heating the water 15 in a range boiler or tank.

It is a more particular object of the invention to provide a heating chamber mounted for horizontal swinging movement to an operative position over one of the 20 range burners or to an inoperative position at one side of the range, said heating chamber being connected by inlet and return conduits to the boiler or tank, such connection being shut off when the chamber is 25 swung to its inoperative position.

It is another important object of the invention to provide improved means for retaining the heat contiguous to the walls of the heating chamber so that the water will 30 be very quickly heated to a high temperature.

With the above and other objects in view, my invention consists in the novel features of construction, combination and arrangement of parts to be hereinafter more fully 35 described, claimed and illustrated in the accompanying drawing, in which,

Figure 1 is a plan view showing my improved water heater employed in connection 40 with an ordinary gas range, the heating chamber being shown in operative position in full lines and in an inoperative position in dotted lines;

Fig. 2 is an enlarged vertical section taken 45 on the line 2—2 of Fig. 1; and

Fig. 3 is a section taken on the line 3—3 of Fig. 1.

Referring in detail to the drawing, R designates a gas or oil burning range provided 50 with the usual spaced burners indicated at B, and W indicates the water boiler or tank suitably mounted in spaced relation to the range or stove.

A bracket indicated generally by the number 55 5, is suitably secured to one side of the range R, said bracket having vertically

spaced arms 6. In these bracket arms, the upper and lower ends of a pipe or tube 7 are suitably secured against rotation, and this pipe is provided with a central division 21 or partition wall 8 therein, thereby separating the interior of the pipe into two non-communicating water receiving compartments 9 and 10 respectively.

The water heating chamber 11 which is 25 preferably of galvanized sheet iron construction and of triangular form in cross-section, is provided in one of its end walls with the vertically spaced nipples 12 and 13. Each of these nipples has a ring or annulus 70 14 formed upon its outer end, the bore of the nipple opening through the inner wall of said ring. A gasket 15 is suitably secured within each of the rings 14 and also has an opening 16 therein coinciding with 75 the bore of the nipple. The spaced rings 14 are engaged upon the fixed vertical pipe 7 respectively above and below the division or partition wall 8 therein, and the said fixed pipe is provided with ports 17 and 18 80 respectively, with which the bores of the nipples 12 and 13 are adapted to register when the heating chamber is disposed in its operative position. Between the rings 14, a spacing collar 19 is suitably fixed upon the 85 vertical pipe 7.

To the lower compartment 9 of the pipe 7, a water conducting pipe 20 is connected at one of its ends and has its other end connected to the bottom of the water boiler 90 W. A similar return pipe 21 is connected to the upper compartment 10 and to the top of the boiler or tank.

A sheet metal hood or cover 22 is disposed over the water heating chamber 11 95 and is provided in one of its end walls with spaced slots 23 to receive the respective nipples 12 and 13, said cover having limited vertical movement with respect to the heating chamber. The inner walls of this cover 100 22 are lined with asbestos or other non-heat conducting material shown at 24, and the longitudinal end edges of said cover, when in its normal position, project downwardly below the base wall of the heating chamber 11 and are adapted to rest upon the stove or range around the burner B, as clearly shown in Fig. 2. Thus, the heat is 105 retained or held between the walls of the hood or cover so that the walls of the heating chamber 11 will soon become very 110 highly heated.

From the above description and the accompanying drawing, the manner of operation of the device will be readily understood. When it is desired to heat the water in the 5 boiler or tank W, the heating chamber, together with the inclosing cover or hood, is swung from the dotted-line position in Fig. 1 to the full-line position over one of the burners B. The cover 22 is, of course, lifted 10 slightly so that it will not impede this horizontal swinging movement of the heating chamber. Upon releasing the cover, it will drop downwardly and rest upon the range. In such movement of the heating chamber, the 15 rings or eyes 14 and the gaskets therein are turned upon the fixed pipe 7 so as to register the openings in the gaskets and the bores of the nipples 12 and 13 with the ports of the respective compartments 9 and 10. The cold 20 water enters the compartment 10 through the pipe 20 and passes through the lower nipple 13 into the chamber 11. The burner flame contacting with the bottom wall of the chamber, soon heats the water which rises through 25 the nipple 12 and the upper compartment 9 of the pipe 7 and the pipe or conduit 21, and is thus returned to the boiler. In this manner, it will be seen that there is a continuous circulation of water between the 30 chamber and the boiler or tank, the colder water at the bottom of the boiler continuously replacing the heated water in said chamber until the entire contents of the boiler is heated to the desired temperature. 35 After heating the water, the hood or cover 22 is lifted slightly and said cover, together with the heating chamber 11, swung to the dotted-line, inoperative position shown in Fig. 1, and in such swinging movement the 40 bores of the nipples are moved out of registering relation with the ports of the pipe 7 and said ports tightly closed by means of the gaskets 15, thus effectually cutting off the further flow of the water between the heating chamber and the tank or reservoir. 45

From the above, it will be seen that I have devised a very simple, as well as serviceable and convenient water heating device for use in connection with gas or oil ranges, whereby 50 water may be very quickly and highly heated in sufficient quantities for domestic use. The supporting bracket 5 may be mounted either upon the frame of the stove or range or upon the wall adjacent thereto. The water heating chamber 11 can also be made in various 55 other shapes than that illustrated and of any desired capacity.

While I have shown and described the preferred construction and arrangement of the 60 several elements herein described, it is to be

understood that the invention is susceptible of considerable modification therein and I, therefore, reserve the privilege of adopting all such legitimate changes as may be fairly embodied within the spirit and scope of the 65 invention as claimed.

Having thus fully described my invention, what I desire to claim and secure by Letters Patent is:—

1. In a water heater, a source of heat, a 70 heating chamber mounted for horizontal swinging movement, said chamber being of triangular form in cross-section and having a horizontal base wall, a water supply and means for establishing a continuous circulation of water between the same and said chamber when the chamber is swung to an operative position over the source of heat, and a 75 heat retaining hood having inclined walls extending in parallel relation to the top 80 walls of the water chamber and vertical marginal walls extending below the horizontal bottom wall of the chamber.

2. In a water heater, a source of heat, a 85 fixed, vertical support having separate water receiving compartments, a heating chamber having spaced nipples mounted upon the support for turning movement and communicating with the respective compartments, a source of water supply, supply and 90 return pipes connecting the same to the respective compartments of said support, and a heat retaining hood extending over the water chamber and having slots in one of its end walls to accommodate the nipples, said nipples limiting the vertical movement of the hood with respect to the chamber. 95

3. In a water heater, the combination with a range having a burner, of a water heating chamber mounted at one side of the range 100 for horizontal swinging movement to operative or inoperative position with respect to the burner, a water reservoir, means establishing a circulation of water between the reservoir and the heating chamber when said 105 chamber is in operative position, said circulation being cut off when the chamber is swung to an inoperative position, and a heat retaining hood inclosing said chamber and having limited vertical movement with respect thereto, said hood resting upon the range around the burner thereof when the heating chamber is in operative position. 110

In testimony whereof I hereunto affix my signature in the presence of two witnesses. 115
